UNITED STATES PATENT OFFICE.

ALLEN P. BOYER, OF GOSHEN, INDIANA.

CARRIER.

No. 835,780.

Specification of Letters Patent.

Patented Nov. 13, 1906.

Application filed May 20, 1905. Serial No. 261,397.

To all whom it may concern:

Be it known that I, ALLEN P. BOYER, a citizen of the United States, and a resident of the city of Goshen, in the county of Elkhart and State of Indiana, have invented certain new and useful Improvements in Carriers, of which the following is a specification.

This invention relates to improvements in carriers.

- 10 The objects of this invention are, first, to provide in a carrier an improved automatic clutch for the power or hoisting rope; second, to provide in a carrier an improved support therefor when in its inner or hoisting position, and, third, to provide in a carrier an improved guide for the power or hoisting rope.

Further objects and objects relating to structural details will definitely appear from 20 the detailed description to follow.

I accomplish the objects of my invention by the devices and means described in the following specification.

The invention is clearly defined and pointed out in the claims.

A structure embodying the features of my invention is clearly illustrated in the accompanying drawings, forming a part of this specification, in which—

- 30 Figure 1 is a detail transverse vertical section of a structure embodying the features of my invention, taken on a line corresponding to line 1 1 of Figs. 2 and 4, the hoisting-rope sheaves and the pulley-blocks K K being shown in full lines. Fig. 2 is a detail side elevation view looking from the right hand of Fig. 1. Fig. 3 is a detail sectional view taken on a line corresponding to line 3 3 of Fig. 2. Fig. 4 is a detail sectional view 40 taken on a line corresponding to line 4 4 of Fig. 1. Fig. 5 is a vertical sectional view of the clutch blocks or members E and F with their supports removed from the frame, taken on a line corresponding to the sectional lines of Fig. 1.

In the drawings the sectional views are taken looking in the direction of the little arrows at the ends of the section-lines, and similar letters of reference refer to similar parts 50 throughout the several views.

Referring to the drawings, the track A is shown suspended from the rafters A'' of a building by hangers A'. This track may be of any desired form or construction, but I prefer to use angle-iron, as is illustrated. The carriage C is suspended from the track

by the arms B, on the upper ends of which are carrying-wheels b. Arranged within the carriage is a frame D, adapted to reciprocate vertically therein. The carriage is provided with suitable vertical ways c for the reciprocating frame. The reciprocating frame is held normally upward by the springs D''. These springs are supported by the outwardly-projecting lugs C' on the carriage and engage the outwardly-projecting lugs D' of the reciprocating frame.

A pair of clutch blocks or members E and F are carried by the reciprocating frame. The upper clutch block or member E is secured to the frame by means of downwardly and forwardly inclined links E'. These links are secured to the reciprocating frame by means of pivot-rods e. (See Figs. 1 and 2.) The lower clutch block or member F is carried by the rocking frame F', which is pivotally supported by the pivot-rod f. The clutch member F is pivotally mounted on this rocking frame F'. Stops s s' are provided to limit the movement of the clutch member F on its carrying-frame. (See Figs. 1 and 2.) The clutch member F is arranged on the frame F' in such a relation to its pivot-point that when the frame is rocked rearwardly the clutch member is thrown upwardly. By pivoting the clutch member F on its carrying-frame it retains its proper relation to the clutch member E, whatever the position of the frame F' may be, so that its entire length engages the rope. This, however, is not essential to securing desirable results, although it is of advantage.

The clutch members are operatively connected by means of the teeth f''' on the frame F', and the teeth e' on one of the rear links E', which support the clutch member E. With the parts thus connected when they are thrown forward they are positively retracted from each other, and when they are thrown rearwardly they are positively forced together to engage the rope. The sheave F'' is carried by the frame F'. The journal-pin f' of this sheave is arranged to the rear of the pivot-pin f of the frame, so that when weight is applied thereto the tendency is to rock the frame rearwardly. When, however, power is applied to the hoisting-rope, the tendency is to rock the frame forward, thus releasing the clutch members.

In operation the power or hoisting-rope H is secured to the forwardly-projecting arm d of the reciprocating frame. It is then rove

over the sheaves of the pulley-blocks K, thence over the sheave F', from whence it is arranged through the clutch and over the guiding-sheave G', the journal-pin G or which is carried by the forwardly-projecting arm d of the frame D to the guide-sheave I'.

To relieve the carriage from lateral strain when in the hoisting position, a rest is provided. This rest is mounted upon the frame 10 A'', secured to the rafters A''. The rest consists of a bracket J, having a pair of vertically-arranged rollers I, which engage the shoe d', which is carried by the projecting arm or bracket c' on the carriage. (See Figs. 1 and 15 4.) The hoisting-rope is passed between the rollers, so that when power is applied thereto the parts are guided into and held in their proper position. The shoe d' is preferably provided with suitable seats d'', adapted to 20 receive the rollers I when a load is being hoisted. From the rollers I the hoisting-rope passes over the guide-sheave I', which is mounted on a suitable journal I'', carried by the bracket J. In the lifting of a load 25 the reciprocating frame D is forced downwardly against the tension of the springs D''. Owing to the toggle relation of the supports E' and F' of the clutch blocks or members, the hoisting-rope H has an unrestricted forward 30 movement, but is locked against backward movement so long as the carrier is carrying a sufficient load to overcome the tension of the springs D'', the clutch parts being shown in their engaging position in Fig. 1 of the 35 drawings. These springs are of sufficient strength to carry the parts in their unloaded state, so that the clutch members are then out of engaging relation. To insure the disengagement of the clutch members, a loop-like stop f'' is provided on the forward part 40 of the clutch-carrying frame F', which stop engages the rod f''. Thus arranged, as the frame D is forced upwardly the frame F' is rocked forwardly on its pivot. This rocking 45 movement, it is apparent, retracts the clamping members and frees the rope, so that it may be passed freely in either direction.

I have illustrated my improved carrier in connection with a pair of running-blocks K K', 50 to which the load-securing ropes K' are shown attached. It is evident that the operation of the clutch proper would be the same with a single running-block or if the rope was attached directly to the load.

55 By arranging the parts as I have illustrated and described I secure a clutch device which permits perfect freedom of movement of the hoisting-rope and at the same time automatically locks it, so that the load may be stopped at any point during its elevation.

While I have especially adapted the locking features to a carrier for use as a hay-carrier or the like, it is evident that they are applicable for use in other relations.

60 My improved carrier is comparatively sim-

ple in structure, and at the same time it is very effective. The parts are arranged so that the strain thereon is reduced to a minimum. While I have illustrated the same in the form preferred by me, I am aware that 70 the structure may be considerably varied in details without departing from my invention, and I desire to be understood as claiming the same broadly, as well as specifically, as illustrated.

Having thus described my invention, what I claim as new, and desire to secure by Letters Patent, is—

1. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower 85 clutch member pivoted on said carrying-frame at a point in front of its pivot; stops for limiting the movement of said lower clutch member on its pivot; a toothed connection for said clutch members; a stop on the forward part of said lower-clutch-member-carrying frame; a sheave mounted on 90 said lower-clutch-member-carrying frame at the rear of its pivot-point; a forwardly-projecting arm on said reciprocating frame; a guide-sheave carried by said arm arranged to guide the hoisting-rope to said clutch members; a shoe carried by said carriage; a bracket; a pair of vertically-arranged rollers adapted to engage the said shoe when said 95 carriage is in its inner position; and a guide-sheave arranged in front of said rollers, all coacting for the purpose specified.

2. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower 110 clutch member pivoted on said carrying-frame at a point in front of its pivot; a toothed connection for said clutch members; a stop on the forward part of said lower-clutch-member-carrying frame; a sheave mounted on 115 said lower-clutch-member-carrying frame at the rear of its pivot-point; a forwardly-projecting arm on said reciprocating frame; a guide-sheave carried by said arm arranged to guide the hoisting-rope to 120 said clutch members; a shoe carried by said carriage; a bracket; a pair of vertically-arranged rollers adapted to engage the said shoe when said 125 carriage is in its inner position; and a guide-sheave arranged in front of said rollers, all coacting for the purpose specified.

5 said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

3. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying frame at a point in front of its pivot; a toothed connection for said clutch members; a stop on the forward part of said lower-clutch-member-carrying frame; a sheave mounted on said lower-clutch-member-carrying frame at the rear end of its pivot-point; a forwardly-projecting arm on said reciprocating frame; a guide-sheave carried by said arm arranged to guide the hoisting-rope to 25 said clutch members; a shoe carried by said carriage; a bracket; a pair of vertically-arranged rollers adapted to engage the said shoe when said carriage is in its inner position; and a guide-sheave arranged in front of 30 said rollers, all coacting for the purpose specified.

4. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying frame at a point in front of its pivot; stops for limiting the movement of said lower clutch member on its pivot; a toothed connection for said clutch members; a stop on the forward part of said lower-clutch-member-carrying frame; a sheave mounted on said lower-clutch-member-carrying frame at the rear of its pivot-point; a shoe carried by said carriage; a bracket; a pair of vertically-arranged rollers adapted to engage the said shoe when said carriage is in its inner position; and a guide-sheave arranged in front of said rollers, all coacting for the purpose specified.

5. The combination with a track of a carriage; vertically-arranged ways on said car-

riage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; a toothed connection for said clutch members; a stop on the forward part of said lower-clutch-member-carrying frame; a sheave on said lower-clutch-member-carrying frame at the rear of its pivot-point; a shoe carried by said carriage; a bracket; a pair of vertically-arranged rollers adapted to engage the said shoe when said carriage is in its inner position; and a guide-sheave arranged in front of said rollers, all coacting for the purpose specified.

6. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; a toothed connection for said clutch members; a stop on the forward part of said lower-clutch-member-carrying frame; a sheave mounted on said lower-clutch-member-carrying frame at the rear of its pivot-point; a shoe carried by said carriage; a bracket; a pair of vertically-arranged rollers adapted to engage the said shoe when said carriage is in its inner position; and a guide-sheave arranged in front of said rollers, all coacting for the purpose specified.

7. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movement of said lower clutch member on its pivot; a sheave mounted on said lower-clutch-member-carrying

frame at the rear of its pivot-point; a forwardly-projecting arm on said reciprocating frame; a guide-sheave carried by said arm arranged to guide the hoisting-rope to said 5 clutch members; a shoe carried by said carriage; a bracket; a pair of vertically-arranged rollers adapted to engage the said shoe when said carriage is in its inner position; and a guide-sheave arranged in front of 10 said rollers, all coacting for the purpose specified.

8. The combination with a track of a carriage; vertically-arranged ways on said carriage; a reciprocating frame arranged within said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; a sheave mounted on said lower-clutch-member-carrying frame at the rear of its pivot-point; a forwardly-projecting arm on said reciprocating frame; a guide-sheave 25 carried by said arm arranged to guide the hoisting-rope to said clutch members; a shoe carried by said carriage; a bracket; a pair of vertically-arranged rollers adapted to engage the said shoe when said carriage is in its inner 30 position; and a guide-sheave arranged in front of said rollers, all coacting for the purpose specified.

9. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said frame is held normally upward; an upper clutch member; forwardly-inclined depending supporting-links therefor, carried by said reciprocating frame; a lower-clutch-member-carrying frame pivoted on said reciprocating frame; a lower clutch member 45 mounted on said carrying-frame at a point in front of its pivot; a sheave mounted on said lower-clutch-member-carrying frame at the rear of its pivot-point; a forwardly-projecting arm on said reciprocating frame; a guide-sheave carried by said arm arranged to guide the hoisting-rope to said clutch member; a shoe carried by said carriage; a bracket; a pair of vertically-arranged rollers adapted to engage the said shoe when said carriage is in its inner 50 position; and a guide-sheave arranged in front of said rollers, all coacting for the purpose specified.

10. The combination with a track of a carriage; vertically-arranged ways on said car-

riage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movement of said lower clutch member on its pivot; a sheave mounted on said lower-clutch-member-carrying frame at the rear of its pivot-point; a shoe carried by said carriage; a bracket; a pair of vertically-arranged rollers adapted to engage the said shoe when said carriage is in its inner position; and a guide-sheave arranged in front of said rollers, all coacting for the purpose specified.

11. The combination with a track of a carriage; vertically-arranged ways on said carriage; a reciprocating frame arranged in said ways; lugs on said carriage; springs seated thereon; lugs on said reciprocating frame, arranged to rest upon said springs, whereby said reciprocating frame is held normally upward; an upper clutch member; forwardly-inclined supporting-links therefor, carried by said reciprocating frame; a lower-clutch-member-carrying frame pivoted on said reciprocating frame; a lower clutch member pivoted on said carrying-frame at a point in front of its pivot; a sheave mounted on said lower-clutch-member-carrying frame at the rear of its pivot-point; a shoe carried by said carriage; a bracket; a pair of vertically-arranged rollers adapted to engage the said shoe when said carriage is in its inner position; and a guide-sheave arranged in front of said rollers, all coacting for the purpose specified.

12. The combination with a track of a carriage; vertically-arranged ways on said carriage; a reciprocating frame arranged in said ways; lugs on said carriage; springs seated thereon; outwardly-projecting lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; a sheave mounted on said lower-clutch-member-carrying frame at the rear of its pivot-point; a shoe carried by said carriage; a bracket; a pair of vertically-arranged rollers adapted to engage the said shoe when said carriage is in its inner position.

tion; and a guide-sheave arranged in front of said rollers, all coacting for the purpose specified.

13. The combination with a track of a carriage; a reciprocating frame; springs for returning said reciprocating frame to its normal position; an upper clutch member movably mounted on said frame; a lower-clutch-member-carrying frame pivoted on said reciprocating frame; a lower clutch member pivoted on said carrying-frame; stops for limiting the movement of said lower clutch member on its pivot; a toothed connection for said clutch members; a stop on the forward part of said lower-clutch-member-carrying frame; a sheave mounted on said lower-clutch-member-carrying frame; a forwardly-projecting arm on said reciprocating frame; a guide-sheave carried by said arm arranged to guide the hoisting-rope to said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

14. The combination with a track of a carriage; a reciprocating frame; springs for returning said reciprocating frame to its normal position; an upper clutch member movably mounted on said frame; a lower-clutch-member-carrying frame pivoted on said reciprocating frame; a lower clutch member pivoted on said carrying-frame; a toothed connection for said clutch members; a stop on the forward part of said lower-clutch-member-carrying frame; a sheave mounted on said lower-clutch-member-carrying frame; a forwardly-projecting arm on said reciprocating frame; a guide-sheave carried by said arm arranged to guide the hoisting-rope to said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

15. The combination with a track of a carriage; a reciprocating frame; springs for returning said reciprocating frame to its normal position; an upper clutch member movably mounted on said frame; a lower-clutch-member-carrying frame arranged on said reciprocating frame; a lower clutch member pivoted on said carrying-frame; a toothed connection for said clutch members; a stop on the forward part of said lower-clutch-member-carrying frame; a sheave mounted on said lower-clutch-member-carrying frame; a forwardly-projecting arm on said reciprocating frame; a guide-sheave carried by said arm, arranged to guide the hoisting-rope to said clutch members; a shoe carried by said

carriage; a bracket; a pair of vertically-arranged rollers adapted to engage the said shoe when said carriage is in its inner position; and a guide-sheave arranged in front of said rollers, all coacting for the purpose specified.

16. The combination with a track of a carriage; a reciprocating frame; springs for returning said reciprocating frame to its normal position; an upper clutch member movably mounted on said frame; a lower-clutch-member-carrying frame pivoted on said reciprocating frame; a lower clutch member pivoted on said carrying-frame; stops for limiting the movement of said lower clutch member on its pivot; a toothed connection for said clutch members; a stop on the forward part of said lower-clutch-member-carrying frame; a sheave mounted on said lower-clutch-member-carrying frame; a shoe carried by said carriage; a bracket; a pair of vertically-arranged rollers adapted to engage the said shoe when said carriage is in its inner position; and a guide-sheave arranged in front of said rollers, all coacting for the purpose specified.

17. The combination with a track of a carriage; a reciprocating frame; springs for returning said reciprocating frame to its normal position; an upper clutch member movably mounted on said frame; a lower-clutch-member-carrying frame pivoted on said reciprocating frame; a lower clutch member pivoted on said carrying-frame; a toothed connection for said clutch members; a stop on the forward part of said lower-clutch-member-carrying frame; a sheave mounted on said lower-clutch-member-carrying frame; a shoe carried by said carriage; a bracket; a pair of vertically-arranged rollers adapted to engage the said shoe when said carriage is in its inner position; and a guide-sheave arranged in front of said rollers, all coacting for the purpose specified.

18. The combination with a track of a carriage; a reciprocating frame; springs for returning said reciprocating frame to its normal position; an upper clutch member movably mounted on said frame; a lower-clutch-member-carrying frame arranged on said reciprocating frame; a lower clutch member pivoted on said carrying-frame; a toothed connection for said clutch members; a stop on the forward part of said lower-clutch-member-carrying frame; a sheave mounted on said lower-clutch-member-carrying frame; a shoe carried by said carriage; a bracket; a pair of vertically-arranged rollers adapted to engage said shoe when said carriage is in its inner position; and a guide-sheave arranged in front of said rollers, all coacting for the purpose specified.

19. The combination with a track of a carriage; a reciprocating frame; springs for re-

turning said reciprocating frame to its normal position; an upper clutch member; a lower-clutch-member-carrying frame pivoted on said reciprocating frame; a lower clutch member pivoted on said carrying-frame; stops for limiting the movement of said lower clutch member on its pivot; a sheave mounted on said lower-clutch-member-carrying frame; a forwardly-projecting arm on said reciprocating frame; a guide-sheave carried by said arm arranged to guide the hoisting-rope to said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

20. The combination with a track of a carriage; a reciprocating frame; springs for returning said reciprocating frame to its normal position; and a clutch member movably mounted on said frame; a lower-clutch-member-carrying frame pivoted on said reciprocating frame; a lower clutch member pivoted on said carrying-frame; a sheave mounted on said lower-clutch-member-carrying frame; a forwardly-projecting arm on said reciprocating frame; a guide-sheave carried by said arm, arranged to guide the hoisting-rope to said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

25. The combination with a track of a carriage; a reciprocating frame; springs for returning said reciprocating frame to its normal position; an upper clutch member movably mounted on said frame; a lower-clutch-member-carrying frame arranged on said reciprocating frame; a lower clutch member pivoted on said carrying-frame; a sheave mounted on said lower-clutch-member-carrying frame; a forwardly-projecting arm on said reciprocating frame; a guide-sheave carried by said arm, arranged to guide the hoisting-rope to said clutch members; a shoe carried by said carriage; a bracket; a pair of vertically-arranged rollers adapted to engage the said shoe when said carriage is in its inner position; and a guide-sheave arranged in front of said rollers, all coacting for the purpose specified.

30. The combination with a track of a carriage; a reciprocating frame; springs for returning said reciprocating frame to its normal position; an upper clutch member movably mounted on said frame; a lower-clutch-member-carrying frame pivoted to said reciprocating frame; a lower clutch member pivoted on said carrying-frame; stops for limiting the movement of said lower clutch

member on its pivot; a sheave mounted on said lower-clutch-member-carrying frame; a shoe carried by said carriage; a bracket; a pair of vertically-arranged rollers adapted to engage the said shoe when said carriage is in its inner position; and a guide-sheave arranged in front of said rollers, all coacting for the purpose specified.

35. The combination with a track of a carriage; a reciprocating frame; springs for returning said reciprocating frame to its normal position; an upper clutch member movably mounted on said frame; a lower-clutch-member-carrying frame pivoted on said reciprocating frame; a lower clutch member pivoted on said carrying-frame; a sheave mounted on said lower-clutch-member-carrying frame; a shoe carried by said carriage; a bracket; a pair of vertically-arranged rollers adapted to engage the said shoe when said carriage is in its inner position; and a guide-sheave arranged in front of said rollers, all coacting for the purpose specified.

40. The combination with a track of a carriage; a reciprocating frame; springs for returning said reciprocating frame to its normal position; an upper clutch member movably mounted on said frame; a lower-clutch-member-carrying frame arranged on said reciprocating frame; a lower clutch member pivoted on said carrying-frame; a sheave mounted on said lower-clutch-member-carrying frame; a shoe carried by said carriage; a bracket; a pair of vertically-arranged rollers adapted to engage the said shoe when said carriage is in its inner position; and a guide-sheave arranged in front of said rollers, all coacting for the purpose specified.

45. The combination of a carrying-frame; vertically-arranged ways on said carrying-frame; a reciprocating frame arranged in said ways; lugs on said carrying-frame; springs seated thereon; lugs on said reciprocating frame, arranged to rest on said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movement of said lower clutch member on its pivot; a toothed connection for said clutch members; a step on the forward part of said lower-clutch-member-carrying frame; a sheave mounted on said lower-clutch-member-carrying frame at the rear of its pivot-point; a forwardly-projecting arm on said reciprocating frame; and a guide-sheave carried by said arm arranged to guide the hoisting-rope to said clutch members, for the purpose specified.

50. The combination of a carrying-frame; vertically-arranged ways on said carrying-

frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; a toothed connection for said clutch members; a stop on the forward part of said lower-clutch-member-carrying frame; a sheave mounted on said lower-clutch-member-carrying frame at the rear of its pivot-point; a forwardly-projecting arm on said reciprocating frame; and a guide-sheave carried by said arm arranged to guide the hoisting-rope to said clutch members, for the purpose specified.

27. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; a toothed connection for said clutch members; a stop on the forward part of said lower-clutch-member-carrying frame; a sheave mounted on said lower-clutch-member-carrying frame to the rear of its pivot-point; a forwardly-projecting arm on said reciprocating frame; and a guide-sheave carried by said arm arranged to guide the hoisting-rope to said clutch members, for the purpose specified.

28. The combination of a carrying-frame; vertically-arranged ways on said carrying-frame; a reciprocating frame arranged in said ways; lugs on said carrying-frame; springs seated thereon; lugs on said reciprocating frame, arranged to rest on said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movement of said lower clutch member on its pivot; a toothed connection for said clutch members; a stop on the forward part of said lower-clutch-members.

ber-carrying frame; and a sheave mounted on said lower-clutch-member-carrying frame to the rear of its pivot-point, for the purpose specified.

29. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; a toothed connection for said clutch members; a stop on the forward part of said lower-clutch-member-carrying frame; and a sheave mounted on said lower-clutch-member-carrying frame at the rear of its pivot-point, for the purpose specified.

30. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; a toothed connection for said clutch members; a stop on the forward part of said lower-clutch-member-carrying frame; and a sheave mounted on said lower-clutch-member-carrying frame at the rear of its pivot-point, for the purpose specified.

31. The combination of a carrying-frame; vertically-arranged ways on said carrying-frame; a reciprocating frame arranged in said ways; lugs on said carrying-frame; springs seated thereon; lugs on said reciprocating frame, arranged to rest on said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movement of said lower clutch member on its pivot; a sheave mounted on said lower-clutch-member-carrying frame at the rear of its pivot-point; a forwardly-projecting arm on said reciprocating frame; and a guide-sheave carried by said

arm arranged to guide the hoisting-rope to said clutch members, for the purpose specified.

32. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; a sheave mounted on said lower-clutch-member-carrying frame at the rear of its pivot-point; a forwardly-projecting arm on said reciprocating frame; and a guide-sheave carried by said arm arranged to guide the hoisting-rope to said clutch member, for the purpose specified.
33. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; a sheave mounted on said lower-clutch-member-carrying frame at the rear of its pivot-point; a forwardly-projecting arm on said reciprocating frame; and a guide-sheave carried by said arm arranged to guide the hoisting-rope to said clutch member, for the purpose specified.
34. The combination of a carrying-frame; vertically-arranged ways on said carrying-frame; a reciprocating frame arranged in said ways; lugs on said carrying-frame; springs seated thereon; outwardly-projecting lugs on said reciprocating frame, arranged to rest on said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; stops for limiting the movements of said lower clutch member on its pivot; and a sheave mounted on said lower-clutch-member-carrying frame at the rear of its pivot-point, for the purpose specified.

35. The combination of a carrying-frame; vertically-arranged ways on said carrying-frame; a reciprocating frame arranged in said ways; lugs on said carrying-frame; springs seated thereon; lugs on said reciprocating frame, arranged to rest upon said springs, whereby said frame is held normally upward; an upper clutch member; forwardly-inclined depending supporting-links therefor, carried by said reciprocating frame; a lower-clutch-member-carrying frame pivoted on said reciprocating frame; a lower clutch member pivoted on said carrying-frame at a point in front of its pivot; and a sheave mounted on said lower-clutch-member-carrying frame at the rear of its pivot-point, for the purpose specified.

36. The combination of a carrying-frame; vertically-arranged ways on said frame; a reciprocating frame arranged in said ways; lugs on said carrying-frame; springs seated thereon; lugs on said reciprocating frame, arranged to rest upon said springs, whereby said reciprocating frame is held normally upward; an upper clutch member; forwardly-inclined depending supporting-links therefor, carried by said reciprocating frame; a lower-clutch-member-carrying frame pivoted on said reciprocating frame; a lower clutch member mounted on said carrying-frame at a point in front of its pivot; and a sheave mounted on said lower-clutch-member-carrying frame at the rear of its pivot-point, for the purpose specified.

37. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member pivoted on said carrying-frame; stops for limiting the movement of said lower clutch member on its pivot; connecting means for said clutch members; a stop on the forward part of said lower-clutch-member-carrying frame; a sheave mounted on said lower-clutch-member-carrying frame; a forwardly-projecting arm on said reciprocating frame; and a guide-sheave carried by said arm arranged to guide the rope to said clutch members, for the purpose specified.

38. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member pivoted on said carrying-frame; connecting means for said clutch members; a stop on the forward part of said lower-clutch-member-carrying frame; a sheave mounted on said lower-clutch-frame;

ber-carrying frame; a forwardly-projecting arm on said reciprocating frame; and a guide-sheave carried by said arm arranged to guide the rope to said clutch members, for the purpose specified.

39. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member arranged on said carrying-frame; connecting means for said clutch members; a stop on the forward part of said lower-clutch-member-carrying frame; a sheave mounted on said lower-clutch-member-carrying frame; a forwardly-projecting arm on said reciprocating frame; and a 15 guide-sheave carried by said arm arranged to guide the rope to said clutch members, for the purpose specified.

40. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member pivoted on said carrying-frame; stops for limiting the movement of said lower clutch member on its pivot; connecting means for said clutch members; a stop on the forward part of said lower-clutch-member-carrying frame; and a sheave mounted on said lower-clutch-member-carrying frame, for the purpose specified.

41. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member pivoted on said carrying-frame; connecting means for said clutch members; a stop on the forward part of said lower-clutch-member-carrying frame; and a sheave mounted on said lower-clutch-member-carrying frame, for the purpose specified.

42. The combination of a reciprocating frame; a spring for returning said reciprocating frame to its normal position; an upper clutch member; forwardly-inclined supporting-links therefor carried by said reciprocating frame; a lower-clutch-member-carrying frame pivoted on said reciprocating frame; a lower clutch member arranged on said carrying-frame; connecting means for said clutch members; a stop on the forward part of said lower-clutch-member-carrying frame; and a sheave mounted on said lower-clutch-member-carrying frame, for the purpose specified.

43. The combination of a reciprocating

frame; a spring for returning said frame to its 65 normal position; an upper clutch member movably mounted on said frame; a lower-clutch-member-carrying frame pivoted on said reciprocating frame; a lower clutch member pivoted on said carrying-frame; connecting means for said clutch members; a stop on the forward part of said lower-clutch-member-carrying frame; and a sheave mounted on said lower-clutch-member-carrying frame, for the purpose specified. 70 75

44. The combination of a reciprocating frame; a spring for returning said frame to its normal position; an upper clutch member movably mounted on said frame; a lower-clutch-member-carrying frame pivoted on said reciprocating frame; a lower clutch member arranged on said carrying-frame; connecting means for said clutch members; a stop on the forward part of said lower-clutch-member-carrying frame; and a sheave mounted on said lower-clutch-member-carrying frame, for the purpose specified. 85

45. The combination of a reciprocating frame; a spring for returning said frame to its normal position; an upper clutch member 90 movably mounted on said frame; a lower-clutch-member-carrying frame pivoted on said reciprocating frame; a lower clutch member pivoted on said carrying-frame; connecting means for said clutch members; and a 95 sheave mounted on said lower-clutch-member-carrying frame, for the purpose specified.

46. The combination of a reciprocating frame; an upper clutch member movably mounted on said frame; a lower-clutch-member-carrying frame pivoted on said reciprocating frame; a lower clutch member pivoted on said carrying-frame; connecting means for said clutch members; and a sheave mounted on said lower-clutch-member-carrying frame, for the purpose specified. 100 105

47. The combination of a reciprocating frame; a spring for returning said frame to its normal position; an upper clutch member movably mounted on said frame; a lower-clutch-member-carrying frame pivoted on said reciprocating frame; a lower clutch member arranged on said carrying-frame; connecting means for said clutch members; and a sheave mounted on said lower-clutch-member-carrying frame, for the purpose specified. 110

48. The combination of a reciprocating frame; an upper clutch member movably mounted on said frame; a lower-clutch-member-carrying frame pivoted on said reciprocating frame; a lower clutch member arranged on said carrying-frame; connecting means for said clutch members; and a sheave mounted on said lower-clutch-member-carrying frame, for the purpose specified. 120 125

49. The combination of a reciprocating frame; a spring for returning said frame to its

- normal position; an upper clutch member movably mounted on said frame; a lower-clutch-member-carrying frame pivoted on said reciprocating frame; a lower clutch member pivoted on said carrying-frame; a stop on the forward part of said lower-clutch-member-carrying frame; and a sheave mounted on said lower-clutch-member-carrying frame, for the purpose specified. 5
50. The combination of a reciprocating frame; an upper clutch member movably mounted on said frame; a lower-clutch-member-carrying frame pivoted on said reciprocating frame; a lower clutch member pivoted on said carrying-frame; a stop on the forward part of said lower-clutch-member-carrying frame; and a sheave mounted on said lower-clutch-member-carrying frame, for the purpose specified. 10
51. The combination of a reciprocating frame; a spring for returning said frame to its normal position; an upper clutch member movably mounted on said frame; a lower-clutch-member-carrying frame pivoted on said reciprocating frame; a lower clutch member arranged on said carrying-frame; a stop on the forward part of said lower-clutch-member-carrying frame; and a sheave mounted on said lower-clutch-member-carrying frame; for the purpose specified. 15
52. The combination of a reciprocating frame; an upper clutch member movably mounted on said frame; a lower-clutch-member-carrying frame pivoted on said reciprocating frame; a lower clutch member arranged on said carrying-frame; a stop on the forward part of said lower-clutch-member-carrying frame; and a sheave mounted on said lower-clutch-member-carrying frame, for the purpose specified. 20
53. The combination of a reciprocating frame; a spring for returning said frame to its normal position; an upper clutch member movably mounted on said frame; a lower-clutch-member-carrying frame pivoted on said reciprocating frame; a lower clutch member pivoted on said carrying-frame; and a sheave mounted on said lower-clutch-member-carrying frame, for the purpose specified. 25
54. The combination of a reciprocating frame; an upper clutch member movably mounted on said frame; a lower-clutch-member-carrying frame pivoted on said reciprocating frame; a lower clutch member pivoted on said carrying-frame; and a sheave mounted on said lower-clutch-member-carrying frame, for the purpose specified. 30
55. The combination of a reciprocating frame; a spring for returning said frame to its normal position; an upper clutch member movably mounted on said frame; a lower-clutch-member-carrying frame pivoted on said reciprocating frame; a lower clutch member arranged on said carrying-frame; and a sheave mounted on said lower-clutch-member-carrying frame, for the purpose specified. 35
56. The combination of a reciprocating frame; an upper clutch member movably mounted on said frame; a lower-clutch-member-carrying frame pivoted on said reciprocating frame; a lower clutch member arranged on said carrying-frame; and a sheave mounted on said lower-clutch-member-carrying frame, for the purpose specified. 40
57. The combination with a track of a carriage; a shoe on said carriage; a bracket; a pair of vertically-arranged rollers adapted to engage said shoe when said carriage is in its initial position; and a guide-sheave arranged centrally of said rollers, for the purpose specified. 45
58. The combination with a frame of an upper clutch member movably mounted thereon; a pivotally-mounted lower-clutch-member-carrying frame; a lower clutch member arranged thereon; connecting means for said clutch members; and a sheave mounted on said lower-clutch-member-carrying frame at the rear of the pivot thereof, for the purpose specified. 50
59. The combination with a frame of an upper clutch member movably mounted thereon; a pivotally-mounted lower-clutch-member-carrying frame; a lower clutch member arranged thereon; and a sheave mounted on said lower-clutch-member-carrying frame at the rear of the pivot thereof, for the purpose specified. 55
60. The combination of a reciprocating frame; an upper clutch member mounted thereon; a lower-clutch-member-carrying frame pivoted on said reciprocating frame; a lower clutch member arranged on said carrying-frame; and a stop on the forward part of said lower-clutch-member-carrying frame, for the purpose specified. 60
61. The combination of a reciprocating frame; an upper clutch member mounted thereon; a lower-clutch-member-carrying frame pivoted on said reciprocating frame; and a lower clutch member arranged on said carrying-frame, for the purpose specified. 65
62. The combination of a reciprocating frame; a pair of clutch members carried thereby; a spring for holding said frame normally in one position; and means for opening said clutch members on the return of said reciprocating frame to its normal position, for the purpose specified. 70
63. In a device of the class described, the combination with a main weight-supporting pulley over which the rope runs, of a clutch member having operative connections with the said pulley, and a second clutch member operatively connected with the first clutch member, whereby both clutch members move in unison to clamp the rope. 75

64. In a device of the class described, the combination with a movably-mounted main supporting-pulley over which the rope runs, of a pair of clamping-jaws having operative connections with said pulley, whereby they are moved in unison to clamp the rope, as specified.

In witness whereof I have hereunto set my hand and seal in presence of two witnesses.

ALLEN P. BOYER. [L.S.]
